CUP

Russel Wright, New York, N. Y.

Application December 13, 1950, Serial No. 13,412

Term of patent 7 years

(Cl. D44—9)

To all whom it may concern:

Be it known that I, Russel Wright, a citizen of the United States of America and a resident of the city of New York, Borough of Manhattan, county of New York, and State of New York, have invented the new and original Design for a Cup, of which the following is a specification, reference being had to the accompanying drawings, forming part thereof, in which—

Fig. 1 is a top plan view of a cup embodying my new design;

Fig. 2 is a side elevational view;

Fig. 3 is a vertical sectional view taken on the line 3—3 of Fig. 1; and

Fig. 4 is a rear elevational view thereof.

I claim:

The ornamental design for a cup, as shown.

RUSSEL WRIGHT.
